UNITED STATES PATENT OFFICE.

EDWARD H. BUSCH, OF CINCINNATI, OHIO.

DESIGN FOR A TRUSS-HOOP.

SPECIFICATION forming part of Design No. 30,094, dated January 31, 1899.

Application filed December 19, 1898. Serial No. 899,775. Term of patent 3½ years.

To all whom it may concern:

Be it known that I, EDWARD H. BUSCH, a citizen of the United States, residing at Cincinnati, in the county of Hamilton and State of Ohio, have invented and produced a new and original Design for a Truss-Hoop; and I do hereby declare the following to be a full, clear, and exact description of the same, reference being had to the accompanying drawings, which form a part of this specification.

Figure 1 is a plan of a truss-hoop embodying my new design. Fig. 2 is a sectionized side elevation of the same.

As shown in the drawings, A represents a tapering truss-hoop whose inner edges are rounded off at *a* and *a'*.

I claim as new and of my invention—

The design for a truss-hoop, as herein shown and described.

In testimony whereof I affix my signature in presence of two witnesses.

EDWARD H. BUSCH.

Witnesses:

JAMES H. LAYMAN,
JOHN C. ROGERS.
